(No Model.)

W. C. MCKINNIS.

STEAM VALVE.

No. 312,488.

Patented Feb. 17, 1885.

N. PETERS, Photo-Lithographer, Washington, D. C.

UNITED STATES PATENT OFFICE.

WILLIAM C. MCKINNIS, OF RED BLUFF, ARKANSAS.

STEAM-VALVE.

SPECIFICATION forming part of Letters Patent No. 312,488, dated February 17, 1885.

Application filed September 1, 1884. (No model.)

To all whom it may concern:

Be it known that I, WILLIAM C. MCKINNIS, a citizen of the United States, residing at Red Bluff, in the county of Jefferson and State of 5 Arkansas, have invented certain new and useful Improvements in Steam-Valves, of which the following is a specification, reference being had therein to the accompanying drawings.

This invention pertains to improvements in slide-valves for steam-engines, having for its object, among other things, to reduce friction to a minimum, to effect the adjustment of the parts, to take up or compensate wear, and to 15 promote simplicity of construction; and the invention consists of the combination and disposition of parts, substantially as hereinafter more fully set forth and claimed.

In the accompanying drawings, Figure 1 is 20 a horizontal section of my improved slide-valve. Fig. 2 is a longitudinal section thereof. Fig. 3 is a cross section of the same.

In the embodiment of my invention I employ a valve, A, and steam-chest A', whose 25 ends are closed save where the valve-stem passes through it to exclude from the valve-chamber dirt or other foreign substances. The chest A' is subdivided into the valve-chamber a and the steam-chamber a', the latter communicating with said valve-chamber by openings a² made in the dividing plate or partition a³ between said chambers. The normally lower longitudinal edges of the steam-chest A' are provided with flanges b, which 35 are connected to the cylinder-plate d by screws e e at the corners, which plate, inside of the chest, is thickened up to form the valve-seat B, having steam-ports f f through it.

Intermediately of the screws e are passed 40 through the flanges b, additional adjusting-screws, e' e', which do not, however, pass through the cylinder-plate d, but bear thereon, and are turned in the opposite direction to that in which the fastening-screws e e are 45 turned, whereby it will be observed that with the valve seated upon the elevated or thickened upseat B, (permitting the lower edge-flanges of the chest A' to normally stand off from the cylinder-plate,) upon the wearing 50 away of the valve and its seat said wear can be readily compensated, the screws e being

tightened or turned to the right, while the screws e' are turned in reverse direction. The valve A is disposed in the chamber a of the steam-chest A', and is provided with the usual 55 stem, g. The valve A is provided with live-steam ports h h and the intermediate exhaust-steam port, h'. Said live-steam ports are arranged well toward the ends of the valve, while in one side of the valve (that side next to the 60 cylinder-plate or cylinder) said exhaust-steam port is of such length that when one of the live-steam ports is admitting steam to one side of the piston of said cylinder that end of the exhaust steam port most distant from said 65 live steam port will be exhausting into a central pipe, i, arranged to extend vertically through the chamber a' of the chest A'; or it may in practice exhaust directly into said chamber a', from which the exhaust-steam may 70 be discharged through a pipe leading to a point below. Either a long or short valve may be employed without affecting the action of the parts or increasing the friction, the ports being widened in the use of a shorter valve, 75 and elongated when the reverse is the case. This valve is simple in construction and can be used at the side as well as the bottom of the chest, as in the present instance. It can also be used in practice with metallic or steel-spring 80 packing.

Having thus fully described my invention, what I claim, and desire to secure by Letters Patent, is—

1. The chest A', subdivided into valve-chamber a and steam-chamber a', having the flange b connected to plate d by screws e, and adjusting-screws e' e', substantially as shown, and for the purpose described. 85

2. In a steam-valve, the plate d, having integral therewith valve-seat B and steam-ports f f, in combination with the chest A', having flange b, and screws e and e' e', substantially 90 as shown and described.

In testimony whereof I affix my signature in 95 presence of two witnesses.

WILLIAM C. MCKINNIS.
